ROLL MATERIAL DISPENSING DEVICE

William C. Roe, Elyria, Ohio, assignor, by mesne assignments, to Printel Communication Systems, Inc., New York, N. Y., a corporation of New York

Application February 8, 1932, Serial No. 591,527

5 Claims. (Cl. 38—172)

This invention relates to material dispensing devices and particularly to devices for dispensing rolled or reeled strip material.

My invention has numerous applications but I 5 have chosen to illustrate and describe it herein as applied to an apparatus for dispensing a strip of paper from a supply roll.

In various classes of apparatus, illustrative of 10 which is electrically operated quotation tickers, telegraph typewriters etc., it is desirable to feed through the said apparatus a relatively narrow strip of paper and to supply the same from a roll or reel.

It is desirable also to enclose the supply roll 15 of paper in a suitable enclosing means such, for example, as a cabinet or other housing to preserve the same against mutilation, to keep it clean etc.

When the supply roll of paper is concealed 20 from view, it becomes desirable to know the quantity of the supply on the roll as it is continuously used, so that as the supply roll approaches the end of the strip a new roll may be charged into the cabinet to avoid interruption of the strip feed in the said apparatus.

It is therefore one of the objects of my invention to provide a rolled material dispensing device whereby the quantity of the material on a concealed roll may be at all times indicated.

30 Another object of my invention is to provide an improved containing cabinet for a roll of dispensable material such as a paper strip or the like, and provided with an externally visible means for indicating the quantity of material on 35 the supply roll in the cabinet.

Another object is to provide a dispensing cabinet for rolled material provided with externally visible indicating means adapted to indicate the decreasing diameter of the roll of material as it 40 is dispensed from the cabinet.

Another object is to provide a rolled material dispensing cabinet having externally visible indicating means for indicating the quantity of rolled material available in the cabinet for dispensing and which will be simple in construction and in which the indicating means may function without interfering with the replacing of an exhausted or substantially exhausted roll and the installation of a succeeding supply roll.

50 Other objects will be apparent to those skilled in the art to which my invention appertains.

My invention is fully disclosed in the following description taken in connection with the accompanying drawing, in which:

Fig. 1 is a view illustrating a mechanism embodying my invention and showing in cross-section a part of an enclosing cabinet therefor;

Fig. 2 is a view taken from the plane 2 of Fig. 60 1; and

Fig. 3 is a view taken from the plane 3 of Fig. 1.

Referring to the drawing, I have shown at 1 and 2 side walls of an enclosing cabinet, the walls being represented fragmentarily to simplify the drawing, but which as will be understood by those skilled in this art may be of any desired extent to completely enclose the roll of dispensable material, 3, to be referred to later. The cabinet may also comprise a rear wall 4 and a wall opposite the wall 4 which is not shown in the drawing inasmuch as the cabinet is illustrated in cross-section as above mentioned. The walls 1, 2 and 4 may be provided with a closing door 5 hinged to the panel 1 as at 6 and adapted to be latched to the panel 2 as, for example, by the device indicated generally at 7 comprising an eye 8 on the wall 2 and a hook 9 pivoted on the door 5.

Upon the door 5 and internally of the cabinet thus provided is secured a bracket 10 comprising a foot 11 secured to the door 5 as by screws 12 20 and comprising an upstanding post 13 to the upper end of which is pivotally mounted a bell crank device 14, the pivot connection thereof comprising a screw 15 having a reduced portion 16 and a threaded portion 17 threaded into the 25 post 13.

The bell crank device 14 pivots upon the reduced portion 16 of the screw 15 and comprises a forwardly upwardly extending arm 18 and a downwardly extending arm 19 at an angle to the 30 arm 18.

At the outer free end of the arm 18, it is provided with a stub shaft 20 upon which is rotatably mounted a roll 21 of dispensable material such as a strip of paper, the strip being indicated at 22 35 and adapted to be dispensed from the roll 21 by the rotation of the latter upon the shaft 20, the strip extending from the roll 21 through a suitable slot or other perforation 23 in the door 5.

The periphery of the roll 21 rests upon a roller 40 support 25, being maintained thereagainst preferably by the action of gravity on the roll 21 and the roller 25 is rotatably supported on the shank of a screw 26 threaded into a post 27 which has a horizontal foot 28 secured to the inner face 45 of the door 5 as by a screw 29.

A disc or other plate 30 is secured to the door 5 inwardly thereof as by screws 31—31 and has pivotally mounted thereon a dial finger 32, the pivot connection being provided by a screw 33 50 screwed into the plate 30 and extending through a suitable perforation in one end of the dial finger 32. The dial finger 32 is disposed generally parallel and spaced inwardly from the door 5 and at its end opposite the pivot 33 is bent to 55 the right at substantially a right angle and extends through an arcuate slot 35 in the door 5 and on the extreme end portion where it emerges outwardly through the slot 35 is again bent into a direction parallel with the outer surface of 60

the door 5 as at 36 to provide an indicating point. An intermediate portion of the dial finger 32 is provided with an upstanding post 37 having adjacent its free end a neck 38 formed therein. A connecting link in the form of a wire 40 has one end bent to encircle the neck 38 and at its opposite end is bent to form a hook which is hooked into a perforation 41 in the end of the arm 19.

10 Upon the outer surface of the door 5 and substantially coextensive with the arcuate slot 35 is an indicating scale comprising suitable subdivision marks 42 and having the characters E and F at the extreme ends of the scale which signify the words "empty" and "full" respectively. The scale marks 42 and the slot 35 are arcuate around the center of the pivot 33.

15 The length of the link 40 and the relative positions of the arms 18 and 19 are so provided that when the roll 21 is full of strips to be dispensed, and when the roll rests upon the roller 25, the indicating point 36 of the dial finger 32 will indicate the scale division corresponding to the letter "F" and thus indicate that the full roll of material is in the cabinet.

20 The strip 22 may now be dispensed out through the slot 23 and as the roll 21 diminishes in diameter, the arm 18 is moved correspondingly clockwise as viewed in Fig. 1, the action of gravity 25 maintaining the decreasing periphery of the roll 21 always in contact with the roller 25. This exerts a pull upwardly as viewed in Fig. 1 of the link 40 through the agency of the arm 19 and moves the dial finger 32 clockwise as viewed 30 in Fig. 2, causing the indicating point 36 to move upwardly over the scale, Fig. 3, toward and ultimately reaching a position adjacent the character "E".

35 Thus the indicating point 36 indicates at all times the quantity of dispensable material still 40 on the roll 21.

45 When the roll is exhausted or when it is desired to renew the same, the door 5 may be opened by unhooking the latch 7 and the arm 18 may be turned counter-clockwise as viewed in Fig. 1 to free the roll from the roller 25, and the dispensed roll may be removed and a new 50 one placed upon the stub shaft 20; and as will be readily understood, this simple operation is not in the least degree interfered with by the presence of the indicating mechanism comprising the link 40, finger 32 etc.

55 When it is desired that the roll 21 shall move by gravity and against the roller 25 and be maintained thereagainst, the cabinet may rest normally upon the wall 2. However, the cabinet may be disposed to rest upon the wall 4, in which case, a spring 50 may be provided secured at one end to the cabinet wall 1 and at the other 60 end to the arm 19 to resiliently constrain the bell crank device 14 toward clockwise movement to maintain the roll 21 against the roller 25.

65 My invention is not limited to the exact details of construction shown and described. Many changes may be made therein without departing from the spirit of my invention or sacrificing its advantages.

I claim:

70 1. In a roll material dispensing device, a cabinet, a hingingly movable closure member for the cabinet, a movable supporting member adapted to rotatably support a roll of material to be dispensed, a stationary abutment engageable by the periphery of the roll of material, a movable

indicating means so connected with the supporting member as to be moved by movement of the supporting member upon diminution of the roll diameter occasioned by dispensing material from the roll, the supporting member and the abutment being mounted on said closure member whereby they are adapted to be moved outwardly from the cabinet with the closure member whereby the roll material may be easily replaced.

2. In a roll material dispensing device, a cabinet, a hingingly movable closure member for the cabinet, a movable supporting member adapted to rotatably support a roll of material to be dispensed, a stationary abutment engageable by the periphery of the roll of material, guide means in the closure member adapted to have an unwound portion of the material projected therethrough and a dispensing pull on the said unwound portion externally of the cabinet causing pressure to be directed against the abutment by 20 the roll, and the supporting member and the abutment being mounted on said closure member and movable therewith externally of the cabinet to permit easy replacement of a roll of material.

25 3. In a roll material dispensing device, a cabinet, a closure member for the cabinet hingingly movable, a movable support means for rotatably supporting a roll of material to be dispensed, a stationary abutment engageable by the periphery of the rotatable roll, a movable indicating means visible externally of the cabinet operable by movement of the support means upon diminution of the roll diameter occasioned by dispensing material from the roll, the supporting member and the indicating means being mounted 30 on said closure member and movable outwardly therewith from the cabinet to permit replacement of the roll material.

4. In a roll material dispensing device, a cabinet, a hingingly movable closure member for the cabinet, a movable support means for rotatably supporting a roll of material to be dispensed, a stationary abutment engageable by the periphery of the rotatable roll, a movable indicating means disposed externally of the cabinet, means linking the support means and the indicating means whereby movement of the support means occasioned by diminution of the roll diameter effected by dispensing material from the roll will operate the indicating means, the support means and the abutment being mounted on said closure member and movable outwardly therewith from the cabinet and the support means being movable relative to the abutment in the outward position to effect replacement of a roll of material.

5. In a roll material dispensing device, a cabinet, a hingingly movable closure member for the cabinet and provided with a guide slot adapted to have an unwound portion of material projected therethrough, a movable support means mounted on the inner face of the closure member adapted to rotatably support a roll of material to be dispensed, a stationary abutment mounted on the closure member intermediate the support means and the guide slot and adapted to resist pressure by the material roll caused by a dispensing pull on an unwound portion of material, and movable indicating means on the outer face of the closure member operable by movement of the supporting member towards the 60 abutment upon diminution of the roll diameter occasioned by dispensing material therefrom.

WILLIAM C. ROE.
